UNITED STATES PATENT OFFICE.

JOHN N. HOFFMAN, OF FOREST GROVE, OREGON.

ROPE-TIGHTENER.

1,248,328.

Specification of Letters Patent.

Patented Nov. 27, 1917.

Application filed March 22, 1917. Serial No. 156,665.

To all whom it may concern:

Be it known that I, JOHN N. HOFFMAN, a citizen of the United States, residing at Forest Grove, in the county of Washington 5 and State of Oregon, have invented certain new and useful Improvements in Rope-Tighteners; and I do declare the following to be a full, clear, and exact description of the invention, such as will enable others 10 skilled in the art to which it appertains to make and use the same.

My invention relates to rope tighteners and more particularly to that class of tighteners which are designed to tighten tent 15 ropes and the like.

The principal object of my invention is to provide a tightener in which the rope is at all times disposed in the line of strain and which thereby causes the strain to be 20 distributed in such a manner along the rope as to insure of its greatest holding power.

Another object of my invention is to provide a device of this character in which the rope may be adjusted at one side of the 25 tightener and in such a manner that the rope will not be held in any sharp bends, thereby eliminating unnecessary wear and strain upon the rope and to this end the invention resides in the novel construction 30 of parts to be hereinafter described and claimed, other objects of the invention appearing in the description taken in connection with the accompanying drawings which form a part of this application and in which:

35 Figure 1 is a side elevation of my improved tightener;

Fig. 2 is a central longitudinal section of the same, the rope being shown in plan view;

40 Fig. 3 is a top plan view;

Fig. 4 is a transverse section on the line 4—4 of Fig. 1;

Fig. 5 is a transverse section on the line 5—5 of Fig. 1; and,

45 Fig. 6 is a plan view of the blank from which my tightener is constructed.

Referring particularly to the drawing in which like reference numerals indicate like parts, the numeral 1 designates my preferred form of tightener which is composed of a flat rectangular metallic blank and which may be made of sheet steel, brass, copper or any other suitable metal and is provided with straight, longitudinal and 55 end edges. Adjacent one end and disposed along the central longitudinal line of the

blank is a longitudinally elongated aperture 2 being of a sufficient width to receive a rope therethrough which is hereinafter to be described. In the construction of my 60 tightener, the blank is bent along its central longitudinal line in order to form a U-shaped member having walls 3 which are disposed with a sufficient width therebetween to accommodate a rope therein. The 65 walls 3 of the U-shaped member are bent inwardly toward each other until they will meet on the end of the blank adjacent the aperture 2 and are continued in this bent formation to a point spaced slightly from 70 the edge of the aperture 2. These inwardly bent portions of the walls 3 are designated at 4 and in their bent position form a tube 5 at the end of the member. The other end of the member is formed in a similar manner, having the bent portions of the walls 75 extending inwardly to an equal distance with the walls of the other end.

This construction serves to provide tubes at each end of the tightener and leaves a 80 central open portion 6 for a purpose to be hereinafter described. Through the tube formed on the end of the tightener adjacent the aperture 2 is passed one end of a rope 7 which is bulged or provided with a retaining ring in any suitable manner on its inner end to frictionally bind the rope in the tube and hold it secure to the tightening member at its end as clearly illustrated in Fig. 2. The rope is then continued outwardly 90 through the tube and looped around the post or peg to which it is desired to fasten the rope after which it is carried upwardly through the aperture 2 disposed in the bottom of the tightener into the open central 95 portion 6, after which it is extended through the tube 5 at the opposite end of the tightening member and continued to its point of connection with the tent or to the object to which it is attached.

100 In the operation of my device, when it is desired to apply the tightener, the rope 7 is grasped by the operator in the open central portion 6 and pulled through the tube at the end of the member farthest from the 105 aperture 2 until the desired adjustment has been reached, after which the rope is then pulled downwardly through the aperture in the bottom of the member so that it will be disposed longitudinally along the bottom of 110 the central open portion 6 so that when strain is applied to the rope, the edge 8 of

the elongated aperture will bite into the rope and cause the same to bind the tightening member. When it is desired to loosen the same, it is merely necessary to force the 5 rope upwardly through the aperture in the bottom of the tightening member, after which it may be adjusted through the central open portion and through the tube at the other end of the tightener.

10 While I have shown in the accompanying drawing and specifically described certain details of construction and materials which are used in the manufacture of my tightener, I desire it to be understood that I do not 15 limit myself specifically to these and that any changes in the details of construction may be made which will be embodied in the scope of the appended claim.

I claim:—

20 A device of the character described comprising a substantially flat rectangular sheet metal blank having straight edges bent

along its longitudinal center to form a substantially U-shaped member, the walls of said member being equally bent toward each other for a short distance from each end to form tubes at said ends to receive and guide a rope therethrough and to provide a centrally open portion in the member, said member having a longitudinally elongated 25 aperture in its bottom adjacent one end to receive a rope therethrough, whereby the rope may be adjusted to loop form through the open portion between the aperture and one end of the member, the other end of said 30 member being utilized to secure the end of the rope and form a guide therefor.

In testimony whereof I have hereunto set my hand in the presence of two subscribing witnesses.

JOHN N. HOFFMAN.
